Patented Aug. 7, 1928.

UNITED STATES PATENT OFFICE.

WILLIAM ARTHUR COYTE, OF LONDON, ENGLAND, ASSIGNOR TO J. LYONS AND COMPANY, LIMITED, OF LONDON, ENGLAND.

MEANS FOR LINING CARDBOARD BOXES.

Application filed April 8, 1926, Serial No. 100,760, and in Great Britain May 14, 1925.

This invention relates to machines for inserting linings in cardboard and like boxes so as to make them ready for filling, and is particularly applicable to machines adapted 5 to fill the boxes with material such as ice cream, butter or the like, where it is necessary that absolute cleanliness be observed.

The present invention comprises means 10 for lining cardboard and like boxes with a lining having extensions or flaps, whereby the lining is inserted in the box and its flaps or extensions are bent outwards and downwards over the edges of the box in such a manner as to maintain the box fully open 15 with its lining flaps away from the inside of the box during filling.

When applied to a filling machine in which the boxes are fed to filling position intermittently, the lining inserting device is arranged in the path of the boxes at a position 20 immediately before the filling position.

The flaps or covers of the boxes are held away from the sides of the box by passing them under guide rods extending along a 25 guide way along which the boxes are fed to the lining inserting positions on the machine.

In the preferred construction of the machine the open boxes are fed along a guide 30 way by means of an endless chain, with the flaps of the foldable cover in the open or vertical position.

In order that the details of construction and the action of the invention may be more 35 clearly understood, reference is made to the accompanying drawings in which Fig. 1 is a side elevation of the lining inserting portion of a box filling machine, Fig. 2 a portion of an elevation of a similar machine 40 with the mechanism in a different position, Fig. 3 a partly sectional transverse elevation of Fig. 1, Fig. 4 a plan of a portion of the machine showing the feeding end of the guide rods, Fig. 5 a plan of the lining, 45 having four flap extensions, Fig. 6 is a view on an enlarged scale of a detail of Fig. 3, and Fig. 7 is a perspective view of the box on an enlarged scale. In the machine shown in Fig. 2 the travel of the 50 boxes is in the opposite direction from that in the machine shown in Fig. 1.

In these drawings 25 is the main standard of the machine, 10 the boxes which are fed 55 intermittently into lining and filling positions by projections 48 on an endless chain

11, which passes over a chain pulley 12 at each end of the machine. The chain pulley 12 at the other end of the machine not shown on the drawings is given an intermittent feed movement by means of ratchet and 60 pawl mechanism operated from the power shaft of the machine.

The boxes 10 are fed by the endless chain 11 along a guide way formed between two angle members 62, 62 to which are fixed 65 guide rods 64 and 65 supported by the brackets 74, (see Figs. 1 and 4).

In feeding a box into the guide way 62 of the machine the operator places it therein in such a manner that the main cover will 70 pass under the guide rods 71 and 72, and subsequently the side flap covers will pass under the guide rods 64 and 65 and be bent thereby outwards, and maintained in such position as they are carried along the guide 75 way 62 to the lining inserting position, that is immediately under a lining inserting device 2.

The bending outwards of the side flap covers of the box is facilitated by the ends of the rods 64 and 65 being bent upwards and inward as shown in Fig. 4. The lining inserting device 2 consists of a plunger plate 3 carried by pins 4, 4 which move vertically a small distance in a main 80 lining inserting member 2, so that the plunger plate 3 can drop out or be forced 85 by springs out of a recess formed for it in the base of the member 2, and be held suspended under it. The member 2 is mounted

on a plunger 24 sliding vertically in a 90 bracket 5 fixed on a rod 6 movable vertically in an upper bearing 8 and a lowering bearing 9 fixed on a standard 7. The rod 6 carrying the bracket 5 and the lining inserting member 2 is reciprocated vertically 95 by a lever 13 to which it is connected by a link 18. The lever 13 is carried by a fulcrum shaft 14 mounted on the standard 25 and provided with a roller 15 bearing on a cam 16 rotated by a shaft 17 driven from 100 the power shaft of the machine through gear wheels 48, 49, 50, 51 and 52, in timed relation to the intermittent operation of the box feeding chain 11.

The lining blanks are cut to form four 105 flap or cover portions see Fig. 5 and are placed on a positioning platform immediately under the lining inserting member 2 which is arranged immediately above a box 110 arresting position in the guide way 62. This

platform is constructed of two oppositely movable portions 26 and 27 carried by levers 28 and 29 pivoted to the standard 7 on the shafts 30 and 31.

- 5 The levers 28 and 29 are provided with rollers 32 and 33 which engage the oppositely disposed inclined or cam shaped pieces 34 and 35 (see Fig. 2) fixed on the vertically movable rod 6, the levers being pulled towards each other so as to keep the rollers 32 and 33 against the cam shaped pieces 34 and 35, by means of a spring 36 of which the ends are fixed on the levers. The platform portions 26 and 27 are detachable from the ends 10 of the levers and are provided with slots 37 and 38 which can slide on bolts 39 whereby their height above the guide way 62 can be adjusted.

In order to press the flaps of the lining 20 over the flaps and sides of the box, above the lining inserting device 2 and fixed to the bracket 5 are inclined pushing plates 139 (see Fig. 3) adapted to carry the flaps of the lining over the corresponding flaps of 25 the box and force them into gripping contact therewith and at the same time forcing the side flaps of the lining under the guide rods 64 and 65. The lining flap extending over the front side of the box which has no 30 front cover flap is pressed against the front side of the box by a plate 40 (see Fig. 2) carried on the end of a lever 41 pivoted at 42 to collar 45 vertically adjustable on an extension 46 of the bracket 5, (see also Fig. 3); Fig. 2 is a view taken from a machine in which the travel of the boxes is in the opposite direction to that of Fig. 1.

40 The other end of the lever 41 is provided with a roller 43 adapted to engage a cam piece 44 fixed on the plunger 24. The roller 43 is held against the cam 44 by means of a spring 47.

During the operation of the machine a box 10 is placed by the operator on the guides 45 62 under an arched member 70 (see Figs. 1 and 4) with the front edge of the box leading, so that when the box is carried along by a projection 48 on the chain 11 the cover of the box will be bent downwards by the 50 rods 71 and 72 the ends of which are bent upwards and secured by nuts 73 to the arched members 70. As the box 10 is carried farther along by the chain its side flaps are bent down by passing under the rods 64 and 65. The box now continues its journey with the cover and side flaps fully extended 55 outwards until it arrives immediately under the lining inserting mechanism.

After the box arrives at the lining inserting position, a lining previously placed in position across the platforms 26 and 27 is forced down into the box by the lining inserting member 2; the downward movement of the rod 6 to effect this operation also, by 60 means of the cams 34 and 35, moves the plat-

form carrying levers 29 and 28 outwards immediately after the lining inserting member 2 engages the lining, and before the pushing plates 139 reach the platforms 26 and 27 which are provided with cut away 70 portions to allow the member 2 to pass through them when they are closed. The outward movement of the levers 29 and 28 is sufficient to move the platforms 26 and 27 sufficiently out of the way to enable the 75 pushing plates 139 to pass below the platforms 26 and 27 and allow the lining inserting mechanism to complete its operation.

During the downward movement of the lining inserting device, the members 3 and 2 80 carry the lining into the box leaving in the first instance its side flaps extending over the sides of the box, these side flaps are however, immediately afterwards engaged by the inclined pushing plates 139 which are then 85 sufficiently close to the box to prevent the outer edges of the flaps from passing under them, and which engage the side flaps of the lining in such a manner as to force them over those of the cover into sufficiently close contact therewith as to remain there during the subsequent filling operation. The continued movement of the bracket 5 carrying the inclined pushing plate 139 is provided for, 90 after the member 2 is arrested in the box by 95 the plunger 24 of the member 2 sliding in the bracket 5.

This continued movement of the bracket 5 also causes the pushing plates 139 after they have pushed the inner portions of the side 100 flaps of the lining against those of the box, to depress the side flaps of the box and bend the outer portions of the flaps of the lining over the rods 64 and 65 and carry them sufficiently below the rods 64 and 65 and to enable them to fall on the cover flaps, so that on the upward movement of the bracket 5 the flaps of both the lining and the cover 105 will be held under the rods 64 and 65. The portion of the lining extending over the 110 main cover is bent over it in the same manner as the side portions by an inclined pushing plate 139 while the front flap of the lining is bent over and against the front side 115 of the box by the plate 40 carried by the pivoted lever 41 and operated as described above. When the plunger 24 is arrested by the member 2 in the box it also arrests the cam piece 44, and as the fulcrum of the lever 41 is carried by the collar 45 secured to 120 the sliding bracket 5, the roller 43 engages the temporarily fixed cam 44 and so moves the plate 40 to press the front flap of the cover against the front edge of the box.

On the upward stroke of the rod 6 the reverse operations take place, the bracket 5 in rising during its initial movement leaves the lining members 2 in the box for a time so that the roller 43 of the lever 41 will, by the action of the spring 47, ride over the cam 44 130

and so lift the plate 40 away from the sides of the box. Also during the initial upward movement of the lining member 2, the plate 3 remains in contact with the bottom of the box and so allows the member 2 to free itself from the lining and admit into the box a small quantity of air and so ensure that the lining will be left accurately in place in the box before the lining mechanism rises free of the box. Further upward movement of the sliding rod 6 moves the rollers 32 and 33 off the cam pieces 34 and 35 and allows the spring connecting the levers 28 and 29 to return the platforms 26 and 27 into a position ready to receive a lining for the next box carried by the chain into lining inserting position.

What I claim and desire to secure by Letters Patent is:—

- 20 1. A machine for inserting a lining having flap extensions into a box and for bending the flaps outwards and downwards over the edges of the box, comprising a reciprocating lining inserting member movable vertically in and out of the box, and a slidable plunger plate, the plunger plate being arranged to form the end of the lining inserting member and to slide axially from the same a limited distance during its upward movement after inserting a lining in the box.
- 25 2. A machine for inserting a lining having flap extensions, into a box and for bending the flaps outwards and downwards over the edges of the box, comprising a reciprocating lining inserting member having at its sides downwardly extending inclined plates and at its lower end an axially slidable portion of a size and shape to insert the lining in the box, the inclined plates being arranged above the axially slidable lining inserting portion and to engage and turn down the flaps of the lining after the axially slidable lining inserting portion has come to rest in the box.
- 30 3. A machine for inserting a lining having flap extensions on all four sides into a box, comprising means for inserting the lining in the box and then bending three of the lining flaps over the back and side edges of the box and separate means for bending the other flap over the front edge of the box.
- 35 4. A machine for inserting a lining having flap extensions on all four sides, into a box, comprising a reciprocating lining inserting member movable vertically in and out of the box and having at its lower end an axially slidable portion and at its side and near faces downwardly extending inclined plates arranged to engage and turn the side and near flaps of the lining down over the corresponding sides of the box, a cam operated lever mounted in bearings on the front of the lining inserting member and carrying at its lower end a flap engaging

plate, the cam being mounted on the lining inserting member above its axially sliding portion and arranged to operate the lever during the downward movement of the lining inserting member after the axially sliding portion is arrested in the box.

5. A machine for inserting a lining having flap extensions, into a box comprising a vertically reciprocating lining inserting member, and a removable support for holding the lining above the box, and means for removing the lining support immediately after the lining inserting member has carried the lining below the support.

6. A machine for inserting a lining having flap extensions, into a box, comprising a lining inserting member carried by a vertically reciprocating rod and two oppositely disposed lining supporting platforms arranged above the box and carried by cam operated levers pivoted to the frame of the machine, the cam being mounted on the vertically reciprocating rod at such a position that it will remove the platforms from the lining immediately after the lining has been engaged by the lining inserting member.

7. A machine for inserting a lining having flap extensions, into a box, comprising a lining inserting member carried by a vertically reciprocating rod, and two oppositely disposed lining supporting platforms arranged above the box and each carried by a cam operated lever pivoted to the frame of the machine and provided with an operating roller, the cam having oppositely disposed operating edges and being mounted on the vertically reciprocating rod at such a position that its opposite edges will engage the rollers of the levers respectively and operate them to remove the platforms from the lining immediately after the lining has been engaged by the lining inserting member.

8. A machine for inserting a lining having flap extensions, into a box, comprising means whereby the boxes are fed intermittently into filling position, and means whereby the lining is inserted in the box, and its flaps bent outwards and downwards over the edges of the box and maintained in such position during the pauses in the operation of the means for intermittently feeding the boxes to filling position.

9. A machine for inserting a lining having flap extensions, into a box having side flaps and a cover, comprising a guide way, means whereby the lining is inserted in the box and its flaps bent outwards and downwards over the edges of the box, means for feeding the boxes along the guide way intermittently to and beyond lining inserting position, and guide rods arranged adjacent the guide way, the guide rods being arranged to hold the flaps and cover of the box in the open position during their passage along the way to lining inserting position.

10. A machine for inserting a lining having flap extensions, into a box having side flaps and a cover, comprising a reciprocating lining inserting member movable vertically in and out of the box and having at its side and rear faces downwardly extending inclined plates arranged to engage and turn the side and rear flaps of the lining down over the corresponding sides of the box, a 5 guide way for the boxes and guide rods arranged adjacent the guide way, the guide rods being arranged to hold the flaps and cover of the box in the open position during their passage along the guide way to lining 10 inserting position and the downwardly extending inclined plates arranged to engage

and turn down the side flaps of the lining down under the guide rods and over the sides of the box, after the lining inserting member has moved into the box. 20

11. A machine for inserting a lining into a box, comprising a vertically reciprocating lining inserting member having a lower portion the shape of the box movable axially thereon, and a sliding plunger plate arranged to form the end of the lining inserting member and to slide axially therefrom during the upward stroke of the reciprocating lining inserting member. 25

In witness whereof I affix my signature.

WILLIAM ARTHUR COYTE.
